A. E. MAYNARD

LENS CUTTER

Filed July 22, 1922

UNITED STATES PATENT OFFICE.

ALBERT E. MAYNARD, OF SOUTHERBRIDGE, MASSACHUSETTS, ASSIGNOR TO AMERICAN OPTICAL COMPANY, OF SOUTHERBRIDGE, MASSACHUSETTS, A VOLUNTARY ASSOCIATION OF MASSACHUSETTS.

LENS CUTTER.

Application filed July 22, 1922, Serial No. 576,846, and in Great Britain July 6, 1922.

This invention relates to improvements in cutters, and has particular reference to a novel and improved construction of machine particularly adapted for use in the cutting 5 of ophthalmic lenses.

One of the principal objects of the present invention is the provision of a machine of this character which will serve to satisfactorily cut varying shapes of glass surfaces, that is to say, either flat, concave, or convex, and which will present the cutting point substantially normal to said various 10 surfaces whereby the best cutting action is effected.

15 A further object of the present invention is the provision of a self-contained machine of this character which can be so adjusted as to cut a large variety both of sizes and shapes of lenses without the necessity of 20 changing guiding shapes, formers, or the like.

Another object of the invention is the provision of a cutter which shall have novel 25 and improved means for clamping the lens in position on the cutting table and which shall be capable of being swung entirely out of the way to facilitate proper positioning 30 of the lens on the table.

A further object of the invention is the provision in connection with a machine having 35 a plurality of formers, of novel and improved mechanism for selectively presenting any desired former for engagement with the cutter controlling shoe.

Another object of the invention is the provision of novel and improved former engaging mechanism which shall insure absolute reproduction of the shape of former employed in place of mere approximation thereto, as has been the case with prior types 40 of construction, and which shall at the same time insure proper tracking of the diamond when following either elliptical or odd shapes.

45 Other objects and advantages of the present invention should be readily apparent by reference to the following specification taken in connection with the accompanying drawings, and it will be understood that I 50 may make any modifications in the specific details of construction shown and described within the scope of the appended claims

without departing from or exceeding the spirit of the invention.

Figure I represents a perspective view of 55 a machine embodying my improvements.

Figure II represents a vertical sectional view thereof with cutter head in inclined position.

Figure III represents a horizontal sectional view taken as on the line III—III of 60 Figure II, illustrating the construction of the former engaging shoe.

Figure IV represents a fragmentary sectional view of the slide adjusting mechanism 65 and indicator.

Figure V is a top plan view of the modified form of former engaging member.

In the drawings, in which similar characters of reference are employed to denote 70 corresponding parts throughout the several views, the numeral 1 designates the base frame or casting having slidably mounted thereon the lens carriage 3, having a portion overlying the base as at 4 to provide a bearing for the rotary lens supporting table 5, and having a second portion 6 extending inward through the slot 7 in the base, providing a lower or thrust bearing on which the spindle 8 of the lens table rests. A 75 lever 9 intermediately pivoted as at 10 to the base and engaging the bottom of the member 6 serves to raise and lower the carriage to bring the lens into engagement with the cutting point. To retain the lens 11 80 in position upon the table 5, I preferably make use of the clamp 12 swivelled as at 13 to the lens clamp arm 14. This clamp arm is carried by a sleeve 15 which telescopes 85 with a second sleeve 16 inserted in the outer portion of the carriage 3, being guided in its sliding movement by the plunger 17, and having the upstanding threaded rod 18 passing centrally through the sleeves 15 and 16, as well as through the arm 14. A nut 19 90 engaged on the upper end of this rod serves 95 as tightened to draw the arm 14 downward on the rod, thus shortening the normal height of the arm from the table, while to normally press the clamp pad 12 into operative engagement with the lens 11 on the table 5 a spring 20 is contained within the sleeve 16 bearing at its lower end against the plunger 17 and at its upper end against

the abutment 21 on the sleeve 16. To facilitate lifting of the arm 14 and clamp pad against the pressure of the spring, I preferably rotatably mount in the base the rock shaft 22 actuated as by the handle 23 and bearing the heart or other shaped cam 24 on which the plunger 17 normally rests. It will be understood that rotation of the rock shaft and thus of the cam will force 19 the plunger 17 upward lifting the rod 18.

It is to be noted that the nut 19 has a depending collar portion 25 provided with a set screw 26 riding in the groove 27 of the arm 14 so that as the rod is raised it will lift with it the arm 14, this groove permitting of rotation of the nut to adjust the vertical position of the arm, as has been previously described. When the cam has reached its upper limit of movement it will be seen that the projecting pin or lug 28 will then fit within the cut-away or recessed portion 29 of the plunger, further movement bringing it against the shoulder 30, while as the movement is continued the contact of the lug 28 with the shoulder 30 will cause the plunger and associated parts to partially rotate, thus swinging the clamp arm backward toward the rear of the machine and leaving the lens and lens table entirely clear, 25 while reverse movement of the handle 23 will turn the clamp to position above the lens, and then allow it to be brought down by the spring action to securely clamp the lens in place.

30 As has been previously mentioned, the lens table clamp and associated parts are slidably mounted on the base and lifted by rocking of the lever 9 to raise the lens into proper engagement with the cutting point, diamond, or the like, 31, while to facilitate this action I preferably make use of the compressed spring 32 contained in a suitable recess in the base, this spring tending to substantially balance the weight of the lens 35 clamp and associated parts so that but slight pressure will be required on the outer end of the lever 9 to raise the entire device and any binding on account of excess of weight on the right hand over the left hand side of the carriage will be eliminated.

Referring now to the cutter head mechanism, there is slidably mounted, as on the guide 33 at the back of the base 1, the upright slide block 34 to which is pivoted, as 40 at 35 (Fig. II) the tilting head 36, this pivotal movement being controlled by interlocking engagement of the latch 37 with a selected recess or socket 38 of the plate 34, so that the head may be locked in vertical position as in Figure I, or tilted to one side or another, as indicated for example by Figure II. The transverse movement of the slide 34 is controlled by the adjusting screw 39 operable as by the head 40, which is itself held against longitudinal movement, its rota-

tion tending to draw the slide 34 back and forth in the usual manner of structures of this type. To indicate, however, the amount of movement imparted to the slide and thus to the head carried thereby, I secure on the screw 39 the pinion 41 meshing with a second pinion 42 which is mounted in a suitable bracket 43 on the side of the base, and has an outwardly projecting hub portion 44 extending slightly beyond the bracket on which 45 is clampingly secured, as by the screw 45, the dial member 46 provided with graduations 47 registering with the witness mark 48 on the bracket to denote the transverse adjustment of the parts. The advantage of so 50 securing the dial is that the machine may be readily set up and put at a predetermined measured point and the dial then set to correspond. An additional advantage here present resides in the fact that it is frequently desirable in the cutting of lenses to cut them a millimeter or more larger in diameter than the finished edged lens. With this form of dial it is therefore possible for the operator to set the dial one millimeter off 55 true reading, or whatever amount he may desire. He can then set the dial to read at the graduation of size he wishes in the finished lens and the machine will automatically take care of the additional size it is desired to cut so as to leave proper amount for edging, thus eliminating entirely the necessity of the operator remembering to calculate the proper over-size in each instance.

Referring to the cutter mechanism proper, 60 the head 36 is provided with a forward extension or arm 49, in which is rotatably received the outer sleeve 50 bearing on its upper end the drive gear 51, and having slidably but non-rotatably mounted therewithin 105 a second sleeve 52 bearing the head 53, on which are slidably but non-rotatably mounted a plurality of different shapes or formers 54. These formers are secured in position by the lock rod 55 having at its upper 110 end the actuating handle portion 56 and on its lower end the locking plate 57 provided with the locking tongues 58 engaging the under side of the bottom-most former, but adapted on a quarter rotation of the rod to 115 be brought into alignment with the notches 59 of the formers so that the formers may be readily slipped off the head in case it is desired to substitute a different former or set of formers for those ordinarily secured 120 upon the head 53. The slides 59 in the formers fit over the ribs 60 of the head 53 and are thus held against rotation relative to the head so that they will turn with the main supporting sleeve 50 as it is rotated by the 125 gear 51.

An arm 61 is pivoted to the head 36 and is of yoke formation having swivelled between the arms of the yoke the cutter holder 62 bearing at its lower end the cutting point 130

31 which extends just to the axis of the pivot 35, while intermediate the cutter carrier 62 is provided with a contact or abutment plate 63 (see Fig. III) for selective engagement with one of the formers. It will be noted that this member is substantially convex in form so as to provide practically point contact with the edge of the former although having the very slight notch 64. This notch is particularly useful in cutting octagonal or other similar shapes, in that the point or corner of the former will catch in the notch, twisting the member 62 about on its pivot so that the cutter 10 will immediately follow the new line of travel, insuring proper angular cuts, something hitherto difficult if not impossible of accomplishment with prior art constructions. To aid in this tracking action there is 20 mounted upon the contact 63 the slide 65 having the spaced contact jaws 66 which are adapted to engage the former at points equidistant from the contact notch 64 and aid in controlling this tracking movement. This 25 slide is actuated along the contact 63 in the direction of the former as by the springs 67 which gave a light pressure yielding so that the contact may at all times be held against the former but so that the jaws will also contact therewith to control the swinging or 30 tracking movement of the cutting point. The actual pressure of the contact against the former is secured by a suitable spring actuating the arm 61, in the present embodiment this spring being mounted within the casing 68, one end being suitably operatively connected with the cutter arm and the other with the stationary frame.

In operation the head is tilted to the requisite angle for the lens surface to be cut, as 40 determined by the graduations 69. The cutter arm is then held outward by rocking of the bell crank arm 70 carried by the arm 61 and contacting with the side of the portion 49 of the head. The knurled sleeve 71 is then grasped and rotated, this sleeve being mounted for rotation on the gear 51, but against vertical movement with respect thereto. A spring latch 72 serves to stop 45 the member 71 at various selected points of rotation. The member 71 is internally threaded to engage the adjustment block 73 secured on the inner sleeve 52 so that as the member 71 is rotated with respect to the gear it will raise or lower the block 73 and sleeve 52. This raising or lowering of these 50 parts serves to shift the head 53 and formers 54 to bring any desired former 54 into alignment with the contact shoe. When they have reached this point the bell crank lever 55 70 is rocked to releasing position when the contact 63 will engage the former, as is indicated in Figure III of the drawings. It will thus be seen that in the form illustrated 60 four entirely different shapes may be cut or

reproduced on the lens without variance of the machine other than the adjustment just referred to, while any size of this particular shape may be cut by transverse adjustment of the slide 34 through rotation of the head 40 and screw 39. Additional shapes, it is to be understood, may be cut by unlocking the member 57 and substituting a different former or formers for the formers 54 shown on the machine. 75

It will be understood that in the cutting operation it is necessary to relatively shift or move the cutting point and the lens, and in the present instance I prefer to shift the lens, the cutting point being held stationary, except in so far as lateral movement is imparted to it by swinging of the cutter arm occasioned by movement of the former. To accomplish this rotative movement there is on the head 36 the bracket 74 in which is journaled the shaft 75 bearing the bevel gear 76 in mesh with a second gear 77 secured on the lower side of the main gear 51 which is in mesh with the pinion 83 connected by a shaft 84 with a second pinion 78 meshing with the gear teeth 79 on the table 5, so that the upper gear 51 with former and associate parts will be operated synchronously with the table bearing the lens. A telescope connection as at 80 and universal joint or joints 81 in the shaft 84 take care of the increase and decrease in length of the shaft due to the tilting movement of the head, and prevent variation of the parts on account of said tilting movement. A handle 82 serves to rotate the shaft 75 and thus transmit movement to the various parts, while as the lens and formers are rotated the cutter arm and cutting point will be swung in and out to reproduce the necessary shape upon the lens. 100

In Figure V I have illustrated a slightly modified form of former engaging member which includes the supporting arm 85 carrying a head portion 86 supported thereby 110 which carries the diamond holder 87.

Mounted upon the head portion 86 and arranged in opposed relation are the pivoted arms 88, said arms being provided with extensions 89 adapted to be arranged upon opposite sides of the diamond holder 87 and connected together by means of a suitable pivot pin. The outer ends of these arms 88 are provided with curved portions 90 and at the extreme outer ends thereof are the rollers 91 which contact with the former and in order to retain these rollers 91 in direct contact with the former at all times I place between the inner ends of the arms 88 a coil spring 92 which tends to move the inner ends of the arms 88 away from each other thus retaining the rollers 91 into contact with the former so that the diamond cutter 87 will be held against the glass being cut and as the arms 88 are pivoted and spring held for 125 130

pivotal movement they will readily ride over the former whereby to guide the cutter in an efficient manner.

I claim:

- 5 1. In a machine of the character described, a base, a lens support on the base, a cutter member having a cutter adapted to cut a lens supported on the lens support, a lens former support, a former comprising a plurality of exact lens shapes of lenses to be cut rotatably carried by the former support, a former contact member on the cutter member contacting with a selected lens shape, means for moving the former support to bring the 10 selected lens shape into engagement with the contact member, and means for rotating said lens support and former in synchronism, whereby the cutter will cut the lens on the support to the same configuration as the lens 15 shape in contact with the contact member.

- 20 2. In a machine of the character described, a cutter member having a cutter, a contact member on the cutter member, a lens former support, a former comprising a plurality of exact lens shapes of lenses to be cut rotatably carried by the former support, means for 25 yieldingly holding the contact member against a selected lens shape, and means for moving the former to bring the selected lens 30 shape into engagement with the contact member.

- 35 3. In a machine of the character described, a slide, a cutter member having a cutter pivoted on the slide, a contact member on the cutter member, a lens former support, a plurality of exact lens shapes to be cut longitudinally arranged on the former support, means for yieldingly holding the contact member against the lens shapes, and means 40 for moving the lens shapes longitudinally to present the selected lens shape to contact with the contact member.

- 45 4. A lens cutter including a base and a support slidably mounted on the base, said support including a lens supporting portion and means for clamping a lens thereon, the said clamping means being movable with the lens supporting portion, means for varying the normal position of the lens supporting

and the lens clamping portions relative to 50 said base, cam mechanism for controlling the action of the clamping portion, a slide carried by the base, and movable transversely thereof, means to move the slide transversely of the base, indicating means to denote the 55 adjustment of the slide with respect to the base, and a cutter member carried by the slide whereby the cutter member may be moved to various positions over said lens support. 60

5. In a device of the character described, a cutter, a lens support slidable towards and away from the cutter, lens clamping means on the lens support and movable therewith, means for lifting the lens clamp away from 65 the support and swinging it out of line therewith, a second movable support, a cutter head pivoted on the second support, a lens cutter on the pivoted cutter head, and means to position the pivoted cutter head at 70 the required cutting angle of the cutter with respect to the lens being cut and a common base for said supports. 75

6. In a machine of the character described, a slide, a swinging cutter arm having a former contact pivoted on the slide, a shiftable former member engaging the former contact and having a plurality of former shapes each of exact shape as a lens to be cut, means for moving the shiftable former member to selectively present the desired former shape of the lens to be cut to the cutter arm contact and means to move the slide to position the cutter arm to regulate the size of the lens to be cut to the former 85 shape engaging the former contact. 80

7. In a machine of the character described, a slide, a cutter member pivoted on the slide and having a cutter, a former arbor, a plurality of separate former shapes adapted to 90 slip on and off of the arbor means detachably holding said shapes on the arbor, a contact on the cutter member adapted to engage each of the formers, one at a time, and means for moving the former shapes longitudinally of the arbor to engage the selected former shape with the contact. 95

ALBERT E. MAYNARD.
